UNITED STATES PATENT OFFICE.

CARL RASMUSSEN, OF GLENDALE, WISCONSIN.

MOP.

1,403,916.

Specification of Letters Patent. Patented Jan. 17, 1922.

Application filed March 8, 1921. Serial No. 450,665.

To all whom it may concern:

Be it known that CARL RASMUSSEN, a citizen of the United States, residing at Glendale, in the county of Monroe and State 5 of Wisconsin, has invented certain new and useful Improvements in Mops, of which the following is a specification.

The invention relates to mops and has for its object to provide a device of this character 10 comprising a handle member to the end of which is secured an arched bracket which terminates in a transverse clamping member for the reception of one end of a mop. Also to provide a longitudinally and rotatably movable rod extending through the handle and having its forward end provided with an eye for the reception of the other end of the mop, said rod being provided with a handle at its rear end adjacent the end of the mop handle 15 and forming means whereby the rod may be rotated for wringing the mop, thereby obviating the necessity of dirtying the hands by wringing the mop with the hands.

With the above and other objects in view 20 the invention resides in the combination and arrangement of parts as hereinafter set forth, shown in the drawings, described and claimed, it being understood that changes in the precise embodiment of the invention may 25 be made within the scope of what is claimed without departing from the spirit of the invention.

In the drawings:—

Figure 1 is a side elevation of the mop.

Figure 2 is a perspective view of the clamping member.

Figure 3 is a bottom plan view of a mop handle showing the longitudinally movable and rotatably movable rod.

Figure 4 is a vertical sectional view 40 through the forward end of the mop handle.

Figure 5 is a sectional view taken on line 5—5 of Figure 4.

Referring to the drawings, the numeral 1 45 designates a mop handle and 2 one end thereof. Imbedded in the end 2 of the handle is the rectangularly shaped portion 3 of a mop supporting bracket 4. The mop supporting bracket has its body portion 5 offset 50 from axial alignment with the handle and terminates in a downwardly extending portion 6, which portion is secured to an upwardly extending flange 7 of a transversely disposed angle member 8, which angle member 55 forms a clamping jaw, with which clamping jaw a jaw plate 9 cooperates for clamp-

ing and holding the end 10 of the mop 11 when the nuts 12 carried by the bolts 13 are tightened. The clamping member as a whole is preferably in alignment with the center of 60 the handle member for properly balancing the device and also for locating the clamping member in a natural position with relation to the handle member 1.

Rotatably mounted in bearings 14 of collars carried by the handle member 1 and in a longitudinally disposed groove 15 in said handle member 1 is a rod 16. The rod 16 is longitudinally movable in the bearings 14 and the groove 15 and also rotatably mounted whereby said rod may be moved forwardly until its eye 17 which receives the rear end of the mop 11 is disposed adjacent the mop clamping device, thereby allowing the mop to be used in the usual manner or 75 moved rearwardly to the dotted line position shown in Figure 1 thereby allowing the mop to be wrung when the operator grasps the handle member 19 of the rod 16 and imparts a rotary movement to said rod, which action 80 will twist the mop in such a manner that the water will be expelled therefrom. It will be seen that the mop may be wrung without placing the hand in contact with the mop which is the objectionable feature in mops as 85 at present used. It will also be seen that the structure is simple and the parts reduced to a minimum thereby allowing the device to be cheaply constructed.

To wring the mop the operator grasps the 90 handle 1 with one hand and with the other hand grasps the handle member 19 of the rod 16 and pulls said rod rearwardly to the position shown in dotted lines in Figure 1. When the rod 16 is in the position shown in 95 dotted lines in Figure 1, the operator rotates the said rod, which action will twist the mop 11 while it is in substantially a straight position and consequently expel the water from the mop 11.

The invention having been set forth what is claimed as new and useful is:—

1. A mop comprising a handle member, a bracket carried by one end of said handle member, said bracket being offset from alignment with the handle member, the end of said bracket terminating in a transversely disposed clamping member in alignment with the handle member, a mop having one of its ends clamped in said clamping member, a 105 rod rotatably and longitudinally movable in a groove in the under side of the handle mem-

ber, ferrules adjacent the ends of the handle member and maintaining the rod in the groove, one end of said rod terminating in an eye for the reception of one end of the mop, 5 the other end of said rod terminating in a handle member adjacent the rear end of the handle member, said rod forming means whereby said mop may be wrung when desired.

10 2. A mop comprising a handle member, a bracket carried by one end of said handle member and imbedded in the end of the handle member, said bracket being offset from alignment with the handle member, the end 15 of said bracket extending inwardly and terminating in a transversely disposed clamping member in alignment with the handle member, a mop having one of its ends clamped

in said clamping member, a rod rotatably and longitudinally movable in a groove of the 20 under face of the handle member, said rod being maintained in said groove and guided in its longitudinal movement by collars extending around the handle member and around the rod adjacent the ends of the handle, one end of said rod being connected to one end of the mop and a handle member carried by the other end of the rod and forming means whereby said rod may be moved longitudinally and rotated. 25

30 In testimony whereof I affix my signature.

CARL RASMUSSEN.
